CARL W. CEDERBERG AND NILS G. LARSON, OF ATTLEBORO, MASSACHUSETTS, ASSIGNEES TO LARSON TOOL & STAMPING COMPANY, OF ATTLEBORO, MASSACHUSETTS, A CORPORATION OF MASSACHUSETTS

FRAME

Application filed November 10, 1928. Serial No. 318,402.

This invention relates to frames more particularly of the adjustable type that may be readily fitted to number plates, name plates, pictures and the like, of different sizes; and the object of this invention is to provide a frame of this character having end and side bars preferably of channel shape to fit over the edge of the plate and to also provide corner members arranged to adjustably engage the frame bars, means being also provided for connecting together these corner members to bind the frame bars in position about the edge of the plate.

A further object of the invention is to provide yieldable connecting members which act upon the corner members to yieldably connect them together to bind and secure the frame bars together in position about the plate embraced therein.

With these and other objects in view, the invention consists of certain novel features of construction, as will be more fully described, and particularly pointed out in the appended claims.

In the accompanying drawings:

Fig. 1 is a front view showing our improved construction of adjustable frame in position about the margin of a number plate.

Fig. 2 is a rear view showing a binding member and two pairs of links connecting the four corner members of the frame together.

Fig. 3 shows one of the corner members as formed from sheet stock before being folded into shape.

Fig. 4 is a perspective view showing the blank as folded into shape forming the frame bar engaging portions and a connecting ear member.

Fig. 5 is a perspective view showing a short length of one of the channel-shaped frame bars.

Fig. 6 is a sectional elevation showing a corner member as engaging side and end frame bars.

Fig. 7 is a sectional elevation illustrating a rivet as formed from the stock of one of the parts for pivotally connecting one of the other frame parts thereto.

Fig. 8 illustrates modifications showing

three additional ways of connecting the corner members together.

It is found in the practical construction and means for attaching together parts of frames more particularly adapted to be applied to number plates, name plates and the like, of advantage to form the frame parts so that the same may be readily adjusted in size to fit different sizes of plates and to be able to quickly assemble the frame parts on its plate and readily connect and bind all of the parts together about the plate without the use of fastening bolts; and the following is a detailed description of the present embodiment of our invention and showing one arrangement of parts by which these advantageous results may be accomplished:

With reference to the drawings, 10, designates the side bars and 11 the end bars of the frame which are preferably formed in channel shape to different desired lengths and are best illustrated in Fig. 5, and 12 designates the corner members which are preferably blanked out of sheet stock, first into the form illustrated in Fig. 3 and then folded into the form illustrated in Fig. 4 having a channel-shaped arm 13 to fit over and slidably engage the end of the side frame bar; and a second channel-shaped arm 14 arranged to similarly engage the end frame bar 11. Also, this corner member is provided with an ear portion 15 which is folded across its back to extend at an angle of substantially 45° to the side arms. This ear member is pierced as at 16 for the purpose presently described.

In order to connect together these four different corner members, we have herein shown one simple construction which is that of providing two pairs of link members 17, each pair being connected together at one end preferably by a pivot 18 and the opposite end of each link 17 is preferably pivotally connected at 19 to the ear 15 of its corner member. In some instances, connection may be made by a separate rivet and in some instances we may raise the stock from one of the parts to form an integral rivet 20 from the stock, as best illustrated in Fig. 7. In some instances, this integral rivet may

be formed from one of the links while in other instances it may be formed on the ear of the corner member, by which construction it will be seen that the parts may be quickly and inexpensively assembled together.

The connected ends of the link members may then be joined together in any suitable way and we have herein shown a wire spring member 21 with a hook 22 formed on each end of the wire, which may be readily connected to the joined ends of each pair of links, whereby by simply connecting the ends of this spring to the links a tension is applied simultaneously to all four corner members causing them to bind their side bars and end bars firmly about the plate. Also in some instances instead of using the flat link 17, I may employ wire connectors arranged in the manner of any of those shown in Fig. 8, if desired, but any other suitable connector member may be employed for this purpose, the primary thought being that the corner members are caused to bind the side and end frame members about the plate without the use of attaching bolts.

In assembling the frame parts, it is only necessary to select from the several standard sizes the lengths of the side and end frame bars required, set them on the edges of the plate to be framed, position the corner members over the ends of the bars, and connect these corners with the flexible connector.

The foregoing description is directed solely towards the construction illustrated, but we desire it to be understood that we reserve the privilege of resorting to all the mechanical changes to which the device is susceptible, the invention being defined and limited only by the terms of the appended claims.

We claim:

1. An adjustable frame comprising side and end frame bars of channel shape, corner members slidably engaging said frame bars, centrally disposed spring means, and connecting means pivotally secured to each corner member and to said centrally disposed spring means.

2. An adjustable frame comprising side and end frame bars of channel shape, corner members having channel portions slidably receiving the end portions of said side and end frame bars, and means pivotally secured to said corner members and exerting a substantially radial resilient binding action on the corner members to retain the frame members in set position.

3. An adjustable frame comprising side and end frame bars of channel shape, corner members having channel portions slidably receiving the end portions of said side and end frame bars, links pivotally secured to said corner members, and resilient means acting upon said links to bind the corner members and the frame bars in operating position.

4. An adjustable frame comprising side and end frame bars of channel shape, corner members shaped to provide channel portions to receive the adjacent ends of side and end frame bars, each having an attaching member pivotally mounted thereon, and centrally disposed spring means connected to all of the attaching members of the frame thru which all of the corner members are bound together to retain the frame bars in working position.

5. An adjustable frame comprising side and end frame bars of channel shape, corner members each folded from sheet stock to provide channel portions shaped to receive the adjacent ends of side and end frame bars, each corner member also having an attaching member pivotally mounted thereon, and centrally disposed spring means exerting a binding action on all of said corner members to retain the frame bars in set position.

6. An adjustable frame comprising side and end frame bars of channel shape, corner members adjustably engaging said frame bars, two pairs of link members each pair being connected at one end and each link of each pair being connected to one of said corner members, and means for connecting together each pair of links to bind the frame bars and corner members in position.

7. An adjustable frame comprising side and end frame bars of channel shape, corner members adjustably engaging said frame bars, two pairs of link members, each pair being pivotally connected together at one end and each link of each pair being pivotally connected to one of said corner members, and means for connecting together each pair of links to bind the frame bars and corner members together.

8. An adjustable frame comprising side and end frame bars of channel shape, corner members adjustably engaging said frame bars, two pairs of link members each pair being connected together at one end and each link of each pair being connected to one of said corners, and a yielding tension member connecting together each pair of links to bind the corners and frame bars in operating position.

9. An adjustable frame comprising side and end frame bars of channel shape, corner members having channel portions shaped to receive the adjacent ends of side and end frame bars, links pivotally secured to corner members, and resilient means acting through said links to connect together said pairs of corner members to bind the frame bars in position.

In testimony whereof we affix our signatures.

CARL W. CEDERBERG.
NILS G. LARSON.
